US0D1027376S

(12) **United States Design Patent** (10) **Patent No.:** **US D1,027,376 S**
(45) **Date of Patent:** **** May 21, 2024**

(54) **BRA**

(71) Applicant: **Hao Hu**, Hubei (CN)

(72) Inventor: **Hao Hu**, Hubei (CN)

(**) Term: **15 Years**

(21) Appl. No.: **29/820,172**

(22) Filed: **Dec. 20, 2021**

(51) **LOC (14) Cl.** **02-01**

(52) **U.S. Cl.**

USPC **D2/706**

(58) **Field of Classification Search**

USPC D2/702, 707, 708, 709, 710, 706

CPC A41C 3/04; A41C 3/0014

See application file for complete search history.

Primary Examiner — Leanne Was-Englehart

(57) **CLAIM**

The ornamental design for a bra, as shown and described.

DESCRIPTION

FIG. 1 is a perspective view of a first embodiment of a bra design showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a rear perspective thereof, showing in a use state.

FIG. 9 is a front perspective view thereof, showing in a use state.

FIG. 10 is a perspective view of a second embodiment of a bra design showing my new design.

FIG. 11 is a front view thereof.

FIG. 12 is a rear view thereof.

FIG. 13 is a left side view thereof.

FIG. 14 is a right side view thereof.

FIG. 15 is a top view thereof.

FIG. 16 is a bottom view thereof.

FIG. 17 is a rear perspective view thereof, showing in a use state; and,

FIG. 18 is a front perspective view thereof, showing in a use state.

The broken lines depict stitching lines that form part of the claimed design.
